PORTABLE TWO-WAY COIN OPERATED TELEPHONE

Susan M. Peoples, 701 Portland St.,
Baltimore, Md. 21200
Filed May 13, 1969, Ser. No. 17,141

Term of patent 14 years

Int. Cl. D19—03

U.S. Cl. D26—14

FIG. 1 is a perspective view of a portable two-way coin operated telephone for home, office, business establishments, institutions, hospitals, etc. showing my new design;

FIG. 2 is a top plan view;

FIG. 3 is a side view; and

FIG. 4 is a front view thereof.

The rear of the article is plain.

I claim:

The ornamental design of a portable two-way coin operated telephone, as shown and described.
